UNITED STATES PATENT OFFICE.

GUSTAF DALÉN, OF SKARSATRA, LIDINGÖ, STOCKHOLM, SWEDEN.

BURNER FOR INCANDESCENT BODIES.

1,277,392.

Specification of Letters Patent. Patented Sept. 3, 1918.

Application filed May 2, 1916. Serial No. 94,890.

To all whom it may concern:

Be it known that I, GUSTAF DALÉN, a subject of the King of Sweden, residing at Skarsatra, Lidingö, Stockholm, Sweden, have invented new and useful Improvements in Burners for Incandescent Bodies, of which the following is a specification.

The present invention refers to gas burners, provided with incandescent bodies, especially burners of that type, which are employed in search light apparatus, and the invention has for its object to establish a large dispersion of the light bundle in a certain desired direction, say in a horizontal direction. Hitherto for this purpose the burner and the incandescent body have been placed at a distance from the focus, but such an arrangement has the inconvenience, that the light intensity is considerably diminished. The purpose of the invention is to obviate said inconvenience, and also to easily vary the light intensity.

On the drawing Figure 1 is a front view of the burner and its incandescent body. Fig. 2 is a side view of the same.

1, 2 and 3 indicate three burners or outflow openings for a gas mixture, say a mixture of acetylene and oxygen, said burners being placed with their openings horizontally side by side. The two outer burners 1 and 3 are connected with a common gas conduit 4, whereas the intermediate burner 2 is connected with a special gas conduit 5. In front of the burner openings a holder 6 is placed, in which an incandescent body, common to all the burners and made in three parts 7, 8, 9, is mounted slidably laterally by hand or by means of a screw or the like. The holder 6 itself may be mounted slidably in a similar manner if desired. Instead of making the incandescent body in three parts, the same may be made in one single piece. If the incandescent body is made in several parts, said parts abut one another as shown on the drawing. No interruption of the

light bundle is caused by such an arrangement of the incandescent body, which has the advantage, that a defective part of the incandescent body can be exchanged without throwing away the whole incandescent body. By moving the body laterally, new parts of the body are employed successively.

When a light bundle with large dispersion in horizontal direction is desired, all the burners or outflow openings 1, 2, 3 are employed simultaneously. When it is desired to limit the light intensity, the conduit 4 is shut off by means of the stop cock 10, so that only the intermediate burner 2 is operating. Its conduit 5 is provided with a special stop cock 11.

Having now described my invention and ascertained in what manner the same is to be performed, what I claim is:

1. In gas burners, coöperating with incandescent bodies, the combination of a plurality of parallel burner nozzles, placed side by side in alinement with one another, and a common incandescent body, made in a plurality of rectangular pieces, abutting one another with their side edges, the flames burning in said burners striking each of said pieces on one side only.

2. In gas burners, coöperating with incandescent bodies, the combination of a plurality of burner nozzles placed side by side in alinement with one another, a common incandescent body, the outer burner nozzles being connected with a gas conduit, and the intermediate burner nozzle being connected with another gas conduit, said gas conduits each being provided with a cutting off device.

In testimony whereof I have signed my name to this specification in the presence of two subscribing witnesses.

GUSTAF DALÉN.

Witnesses:

WALDEMAR BOMAN,
A. BIORCK.
